ATTORNEY

UNITED STATES PATENT OFFICE

JOHN A. COCA, OF JEANNETTE, PENNSYLVANIA

WALL SURFACING OR FACING UNITS

Application filed December 24, 1931. Serial No. 583,084.

The invention relates to wall surfacing or facing units and more especially to metallic seaming or jointing strips for wall surfacing or facing units.

5 The primary object of the invention is the provision of a plurality of brick, veneer or tile units and seaming or jointing strips, wherein a wall or other surface can be conveniently faced therewith so that the seams or joints between the bricks, veneer or tiles will be closed so as to exclude water or moisture therefrom and smooth and even joints will be had both throughout the extent of the surfacing or facing units and at the corners or edges of a wall.

Another object of the invention is the provision of a structure of this character wherein the employment of fasteners is reduced to a minimum as each seaming or jointing strip requires but two fasteners to hold the same in place when closing a joint between adjacent bricks, veneer or tiles, thus enabling the facing or surfacing of wooden or plastic covered walls without excessive mutilation and also assuring a firm and secure anchorage of the surfacing or facing thereto, the seaming or jointing strips being of novel form and permitting the application without the necessity of a skilled artificer and enables the even setting of whole or half or smaller portions of bricks, veneer or tiles with uniformity and evenness and without excessive labor.

A further object of the invention is the provision of a structure of this character wherein plastic seams or joints in the laying of brick, veneer or tile surfaces or coverings is entirely dispensed with and at the same time a water-tight joint or seam is had between the brick, veneer or tile, the structure being novel in its make-up and is layable with dispatch and without the employment of skilled workmanship.

A still further object of the invention is the provision of a structure of this character which is simple in its make-up, thoroughly reliable and efficient in its purpose, readily and easily applied, neat and attractive in appearance, and inexpensive to manufacture and install.

50 With these and other objects in view, the

invention consists in the features of construction, combination and arrangement of parts as will be hereinafter more fully described in detail, illustrated in the accompanying drawings, which disclose the preferred embodiment of the invention, and pointed out in the claim hereunto appended.

In the drawings:—

Figure 1 is a fragmentary elevation showing the structure in accordance with the invention applied to a portion of a wall.

Figure 2 is a sectional view on the line 2—2 of Figure 1 looking in the direction of the arrows.

Figure 3 is an enlarged sectional view taken on the line 3—3 of Figure 1.

Figure 4 is a perspective view of one of the bricks, veneer or tiles.

Figure 5 is a perspective view of the seaming or jointing strip employed at the face of a wall.

Figure 6 is a perspective view of the seaming or jointing strip as employed at the corner of a wall.

Similar reference characters indicate corresponding parts throughout the several views in the drawings.

Referring to the drawings in detail, A designates a series of bricks, veneer or tiles employed for the surfacing or facing of a wall or the like and each includes a body 10 having a receded edge forming a marginal portion 11 unbroken throughout to form a continuous flange 12 at the opposite longer and shorter edges of said body 10.

The bodies 10 are adapted to be arranged end to end in rows superposed so that the joints between the ends of said bodies will be staggered with respect to each other in a vertical direction and these bodies are designed to be disposed against a backing 13 such as sheet waterproof material which is disposed against the face of the wall to be surfaced or faced.

Located between the bodies 10 is a metallic striping B including substantially U-shaped sections 14 having laterally outturned flanges 15, the U form of said sections 14 providing a channel 16 at the center thereof and between the lateral flanges 15. The sections 14 are

laid between the bodies 10 so that the end of one section will overlap the next adjacent section thereto and the other end underlap the other section next adjacent thereto so that 5 the sections when laid in this manner will have their flanges 15 overlying the flanges 12 of the bodies 10 and engaged through the overlapped ends of said sections 14 are fasteners 17, these being driven into the backing 13 and the underlying wall make-up C. It will thus be seen that the joints or seams between the bodies 10 will be closed by the sections 14 both at opposite longer side edges and shorter end edges of said bodies and will 10 exclude the entrance of water therebetween, while the backing 13 will exclude moisture and air working through the wall make-up C.

Each section 14 extended longitudinally of the bodies 10 at the flange 15 thereof con- 20 fronting the joint between the shorter end edges of said bodies is cut away to provide a slot 18 which is extended to the bottom of the channel 16 in said section and adjacent to this slot 18 is engaged with a cut-into flange 25 15 and short length section 19 which is located between the shorter end edges of adjacent bodies 10 to close the joint or seam therebetween, the flanges 20 of these sections 19 underlying the adjacent flange 15 of the 30 section 14 and in this manner said section 19 is held in place while the slot 18 establishes communication between the channels centrally in the sections 14 and 19 so as to permit water as may be contained therein to flow 35 in a zigzag fashion through the channels of the respective sections and be discharged therefrom at the lowermost portion of the wall make-up C as should be obvious.

In Figure 6 of the drawings the stripping 40 B has its section 21 provided with a right- 10 angular bend 22 so as to be carried about the corner of the wall make-up as is clearly shown in Figure 2 of the drawings.

It will be apparent that whole, half or 45 other portions of a brick, veneer or tile can be anchored in place when laid for wall sur- 110 faces or facing in the use of the stripping and without the employment of cement or other plastic material for seaming or jointing 50 of the bodies 10 in the surfacing and facing of the wall make-up.

The long and short sections 15 and 19 of the stripping can be varied accordingly to the sizes of the bricks, veneer or tiles as may 55 be employed in the laying thereof for the 120 wall surfacing or facing.

It should also be obvious that a minimum use of fasteners for the stripping is required as it is only necessary to employ but two 60 fasteners for each strip in the laying of adja- 125 cent strips in their overlapped fashion, that is, in the laying of the sections 15 as hereto-fore described.

What is claimed is:—

65 In a structure of the kind described, a plu-

rality of flat bodies arranged in rows side by side, the bodies in one row being staggered with respect to the bodies in the next adja- 70 cent row, each body having a receded marginal edge, channeled stripplings interposed be- 75 tween the bodies and having lateral flanges overlapping the receded edges of said bodies, the stripplings between the rows of bodies being overlapped, and fasteners engaged with the overlaps of said stripplings, the stripplings in each row having a slot cut into one side thereof with said slots aligned with stripplings confronting the stripplings of the 80 rows to establish communication between the channels in the stripplings.

In testimony whereof I affix my signature.
JOHN A. COCA.
